UNITED STATES PATENT OFFICE.

SAMUEL R. SMITH, OF CHECOTAH, OKLAHOMA.

DESIGN FOR A BANNER.

Application filed April 14, 1926. Serial No. 17,287. Term of patent 14 years.

To all whom it may concern:

Be it known that I, SAMUEL R. SMITH, a citizen of the United States of America, residing at Checotah, in the county of McIntosh and State of Oklahoma, have invented a new, original, and ornamental Design for a Banner, of which the following is a specification, reference being had to the accompanying drawing, forming a part hereof. The drawing is a face view of a banner showing my design.

I claim:

The ornamental design for a banner, as shown.

SAMUEL R. SMITH. [L.S.]
